Inventor

FRANCÉSE, OLSEN

By Richard B. Owen Attorney

UNITED STATES PATENT OFFICE.

FRANCES E. OLSEN, OF GLENDALE, CALIFORNIA.

HAND BAG.

Application filed January 28, 1924. Serial No. 689,140.

To all whom it may concern:

Be it known that I, FRANCES E. OLSEN, a citizen of the United States, residing at Glendale, in the county of Los Angeles and State of California, have invented certain new and useful Improvements in Hand Bags, of which the following is a specification.

The present invention relates to handbags and has for its principal object to provide a device of this nature having a simple and efficient construction, one which is reliable, convenient, inexpensive to manufacture, durable, attractive in appearance and well adapted to the purpose for which it is designed.

With the above and numerous other objects in view as will appear as the description progresses, the invention resides in certain novel features of construction, and in the combination and arrangement of parts as will be hereinafter more fully described and claimed.

In the accompanying drawings:

Figure 1 is a side elevation of the hand bag;

Figure 2 is an end elevation thereof;

Figure 3 is a plan view partly in section taken substantially on the line 3—3 of Figure 1;

Figure 4 is a vertical section taken substantially on the line 4—4 of Figure 3;

Figure 5 is a detail transverse section taken substantially on the line 5—5 of Figure 4;

Figure 6 is a detail section taken on the line 6—6 of Figure 4; and

Figure 7 is an enlarged detail vertical section taken substantially on the line 7—7 of Figure 1.

Referring to the drawing in detail it will be seen that the major portion of the hand bag is formed from a single sheet of flexible material such as fabric, cloth or the like. This strip of material is folded and sewed so as to form sides 1 and the bottom 2. The edges of the sides and bottom are folded inwardly over upon themselves so as to terminate in flaps 3. The inwardly extending portions 4 are sewed or otherwise fastened to the sides and bottom and the flaps 3 are folded inwardly over upon themselves as is indicated clearly in Figure 3, and as indicated in Figure 2 these end flaps are provided with suitable eyes for receiving a cord 5 whereby the ends of the bag may be closed.

On the inner sides of the sides 1 there are provided pockets 6 preferably disposed adjacent the upper edges thereof. A cover 7 is provided with side flaps 8 adapted to hang over the bag adjacent the sides 1. One of the flaps is permanently attached to the adjacent side 1 while the other flap is detachably associated with the adjacent side by means of a suitable fastening element 9. Carrying straps 10 are fixed to the sides 1 so as to extend over the top of the bag.

From a consideration of the above description taken in conjunction with the drawing it will be seen that the device provided is exceptionally handy in carrying small articles and will hold a considerable number thereof, the number, of course, depending on the size of the bag. It is also to be noted that by letting out the cords 5 the capacity of the bag may be increased.

Although I have described my invention with a certain degree of particularity, it is to be understood that numerous changes in the details of construction, and in the combination and arrangement of parts may be resorted to without departing from the spirit or scope of the invention or sacrificing any of its advantages.

What is claimed is:

1. A handbag of the class described formed from a single sheet of flexible material so as to provide a pair of sides and a bottom, the edges of the sides and bottom being folded upon themselves and fixed thereto and terminating in slots provided with eyes, and cords adapted to be interwoven through the eyes for forming ends for the handbag.

2. A handbag of the class described formed from a single sheet of flexible material so as to provide a pair of sides and a bottom, the edges of the sides and bottom being folded upon themselves and fixed thereto and terminating in slots provided with eyes, and cords adapted to be interwoven through the eyes for forming ends for the handbag and pockets formed interiorally of the handbag on the sides thereof.

3. A handbag of the class described formed from a single sheet of flexible material so as to provide a pair of sides and a bottom, the edges of the sides and bottom being folded upon themselves and fixed thereto and terminating in slots provided with eyes, and cords adapted to be interwoven through the eyes for forming ends for

the handbag and pockets formed interiorly of the handbag on the sides thereof, a cover for the handbag being fixed to one side and provided with a flap overhanging the other side and a fastening element for holding the flap in engagement with the latter mentioned side.

4. A handbag of the class described including a body formed from a single sheet of flexible material so as to provide a pair of sides and a bottom, said sides and said bottom being folded adjacent their edges over upon themselves inwardly, said folded portion being fixed to the sides and the bottom and terminating in a flap provided with

marginal eyes, cords interwoven through the eyes so as to form ends for the handbag, pockets provided on the interior surface of the sides, a cover provided with side flaps one of which is fixed to one side of the body and the other detachably associated with the other side of the body, and handle straps fixed to the sides all in the manner and for the purpose specified.

In testimony whereof I affix my signature in presence of two witnesses.

FRANCES E. OLSEN.
